Primary Examiner — George D. Kirschbaum*Assistant Examiner* — Maria J. Edwards(74) *Attorney, Agent, or Firm* — Andrew F. Young; Nolte Lackenbach Siegel(57) **CLAIM**

The ornamental design for a golf glove, as shown and described.

DESCRIPTION

FIG. 1 is a front top perspective view of a golf glove showing our new design.

FIG. 2 is a rear top perspective view thereof.

FIG. 3 is a front elevation view thereof.

FIG. 4 is a rear elevation view thereof.

FIG. 5 is a right side elevation view thereof.

FIG. 6 is a left side elevation view thereof.

FIG. 7 is a top plan view thereof; and,

FIG. 8 is a bottom plan view thereof.

The broken lines on the exterior of the glove in FIGS. 1-8 depict stitching and form part of the claimed design. The broken lines on the interior of the golf glove in FIG. 8 depict portions of the article that form no part of the claimed design.

1 Claim, 8 Drawing Sheets(56)
